UNITED STATES PATENT OFFICE

166,731

BOTTLE

Royden A. Blunt, Baltimore, Md.

Application August 7, 1951, Serial No. 16,196

Term of patent 14 years

(Cl. D58—6)

To all whom it may concern:

Be it known that I, Royden A. Blunt, a citizen of the United States, residing at Baltimore, Maryland, have invented a new, original, and ornamental Design for a Bottle, of which the following is a specification, reference being had to the accompanying drawing, forming a part thereof.

Figure 1 is a side elevation of a bottle, showing my new design; and

Figure 2 is a top plan view of Figure 1.

The dominant feature of my design resides in the portions shown in full lines.

This application is a continuation-in-part of my application Serial Number D. 7,486, filed January 26, 1950, now abandoned.

I claim:

The ornamental design for a bottle, substantially as shown and described.

ROYDEN A. BLUNT.
